UNITED STATES PATENT OFFICE.

EDWARD H. WAUGH, OF SEATTLE, WASHINGTON.

JOINTING AND MATCHING CUTTER.

1,215,755.

Specification of Letters Patent. Patented Feb. 13, 1917.

Application filed June 30, 1914. Serial No. 848,196.

To all whom it may concern:

Be it known that I, EDWARD H. WAUGH, a citizen of the United States of America, and a resident of the city of Seattle, in the county of King and State of Washington, have invented certain new and useful Improvements in Jointing and Matching Cutters, of which the following is a specification.

The present invention pertains to cutters of the above character, of improved form, combined with rotary cutter heads, and it consists in certain novel features whereby a desired lateral delivery of the chips is obtained and a more finished surface on the stock produced.

For a full understanding of the invention, reference is had to the following specification and the accompanying drawing 20 wherein:

Figure 1 is a fragmentary plan of a matcher head embodying the features of my invention.

Fig. 2 is a side elevation thereof.

Figs. 3 and 4 are fragmentary edge views of adjacent circular cutters, shown as operating on the stock.

Fig. 5 is a fragmentary side elevation of one of the cutters.

Fig. 6 is an edge view thereof, and

Figs. 7 and 8 are elevations illustrating slightly modified constructions.

In carrying out my invention I provide a combined cutter construction, shown as embracing jointing and tonguing cutters having a common throat which flares outwardly or laterally away from the tongue being worked so as to deliver the chips laterally, or away from the cutter-edges there- 40 by overcoming, or in a great measure over-coming, choking of the cutter-throat. Therefore the stock can be fed more rapidly without splintering or tearing the matched face.

Employing like characters of reference to corresponding parts throughout the several views wherein, I have shown my invention incorporated in a double circular cutter or bit construction, 1 indicates a body 50 of cylindrical or disk like body having a transverse, peripheral cut-out 20, the bottom wall *a* of which merges, at its rear portion, in the throats or chip breaks *b* of cutting blades 2, 2, which extend in the general direction of the axis of body 1 and are separated by the peripheral groove 4.

The active portions of the cutter have a particular form enabling the production of a smooth, even surface on the stock. In this connection it will be observed that blades 60 2, 2 have their jointing cutter parts provided with working faces 2', 2' which are beveled rather sharply under these faces, which lead to throats *b* being of such width that they extend inwardly for a compara- 65 tively short distance. Throats *b* which are ground at an inclination to the longitudinal axis of body 1, are curved in cross section, as shown, to form effective chip breaks, diverge and flare slightly from a point, as *c*, 70 midway of the width of groove 4. Therefore, this inclination accomplishes a two-fold function, first, of delivering the chips sidewise so that they will not be crowded in a forward direction, and second, it pro- 75 vides two beveled cutting parts 2'' at the edge of groove 4, extending from faces 2', to the point *c*, which have a shearing action and thereby serve to smoothly cut the outer portion of the side faces and the curved 80 end face of the tongue on the stock. Another apparent advantage resulting from the provision of these diverging throats is that the chips will be delivered from both sides with a resultant balancing influence on the 85 cutter.

One wall of the peripheral, tongue-forming groove, is made to conform to the outline of the finished tongue, while at the other side, the groove is enlarged, this wall 90 lying slightly without the corresponding finished surface of the tongue. The edge at one side thus makes a finished cut, while the edge at the other side makes a roughing cut. These walls of successive cutters are 95 alternated in position, so that the finish cut is made by each cutter at the side where the preceding cutter made a roughing cut, whereby the work done by the finishing cutting edges is reduced to a minimum and 100 they will therefore maintain efficient cutting condition for a maximum time.

The cutters are preferably interposed between flange supports 5 and 6 of a cutter head 7 and secured thereon by fasteners 8. 105

In the modified construction shown in Fig. 7 one of the blades, as 2^a has its jointing cutting edge inclined rearwardly outwardly from groove 4 and the adjacent end portion of body 1, of which blade 2^a 110 is a part, is flared outwardly from groove 4, thus making a conoidal, shape, whereby

the entire cutting edge of the blade will be disposed in the plane of cut and, in operation, produce a shearing cut.

In the modified form shown in Fig. 8, both blades 2^a and 2^b have their cutting edges inclined parallel with the bottom walls of their throats, and both end portions of the body 1^a are flared or coned, such flared portions being inclined oppositely from groove 4. Therefore, the entire cutting edges of both blades will lie in the plane of cut.

This invention is based upon three co-operating features which complement and supplement each other to produce a more perfect result. These are, first, the inclined position of the cutting edges relative to the axial and rotative planes of the head: second, the inclination of the throat or chip-breaking surface lying inwardly of the cutting edge: third, to the formation of the tonguing groove in the cutters so that one side edge forms a roughing cut and the opposite edge a finishing cut, these being reversed in position upon alternate cutters.

The first of these features gives the draw cut which gives smoother surfaces and produces good surfaces in bad material. The second or sidewise inclined throat contributes to a like result and as well produces a better discharge of the chips; and the third produces smoother surfaces on the flanks of the tongues.

Having thus described my invention, what I claim as new, and desire to secure by Letters Patent of the United States of America, is:—

1. A detachable cutter for a cutter head

Copies of this patent may be obtained for five cents each, by addressing the "Commissioner of Patents, Washington, D. C."

having throats formed on its advancing face inward from the cutting edge and inclined to an axial plane to form a forwardly facing apex. 40

2. A detachable cutter for a cutter head having its cutting edge provided with a groove and throats formed on the advancing 45 face inward from the cutting edges and inclined to an axial plane to make a forwardly facing apex at the groove.

3. A detachable disk cutter having a peripheral surface of conical character extending from a side face inward with the larger radius at the outer face and a transversely extending notch extending across said surface at an angle to form a cutting edge which is inclined to an axial plane with the 55 rearwardly positioned end of said cutting edge at the side of said conical surface which is of largest radius.

4. A cutter head comprising a rotative cutter-carrying body, and a series of cutters adjustably mounted about the periphery of said body, said cutters each having two separated jointing edges and a forming groove connecting said jointing edges, the opposite sides of said groove conforming 65 respectively to roughing and finishing shapes and alternate cutters, as mounted upon the body, having said roughing and finishing edges reversed in position.

Signed at Seattle, Washington, this 17th 70 day of June 1914.

EDWARD H. WAUGH.
